(57) **CLAIM**

The ornamental design for a vehicle fire extinguisher mount, as shown and described.

DESCRIPTION

FIG. 1 is an exploded top plan view of the vehicle fire extinguisher mount.

FIG. 2 is an assembled top plan view of the vehicle fire extinguisher mount.

FIG. 3 is a view similar to FIG. 2, but with the vehicle fire extinguisher mount contracted and the side arms rotated to the position as also seen in FIG. 7.

FIG. 4 is a rear elevation view of the vehicle fire extinguisher mount.

FIG. 5 is a left side elevation view of the vehicle fire extinguisher mount.

FIG. 6 is a view similar to FIG. 5, but with the side arm rotated to a second position.

FIG. 7 is a view similar to FIG. 6, but with the mounting bracket also rotated to a second position. FIG. 7 is a side elevation view corresponding to FIG. 3.

FIG. 8 is a perspective view of the vehicle fire extinguisher mount; and,

FIG. 9 is a perspective view of the vehicle fire extinguisher mount with a fire extinguisher mounted thereon.

The broken lines are for illustration purposes and form no part of the claimed design.
